PAPER CUP

Walter E. Amberg, Chicago, Ill., assignor to Universal Paper Products Company, Chicago, Ill., a corporation of Illinois

Application April 17, 1940, Serial No. 330,029

10 Claims. (Cl. 229—53)

This invention relates to a new and improved type of paper cup and more particularly a paper drinking cup and to a new and improved method for the manufacture thereof. The invention is especially concerned with the production of a paper cup which normally is a flat folded cup but which when subjected to a slight hand pressure will open and remain open.

Paper cups as marketed today fall into several classes such as envelope cups, cone-shaped cups, flat bottom cups and wedge-shaped cups. These cups, with the exception of the envelope cups, have a normally open mouth and therefore, are readily filled with liquid. The envelope cups are normally collapsed and have to be pressed open by the hand of the user in order to be filled with a liquid. Furthermore, the envelope cups tend to return to their collapsed form when held in the hand and, therefore, are apt to spill their contents unless the user is very careful. The envelope cups, however, have one outstanding advantage over the other types of cups, namely, they occupy a relatively small amount of space and therefore, are relatively inexpensive to package and ship. Notwithstanding this advantage in favor of the envelope cups, the disadvantage of their normal tendency to collapse is so great that in many instances the other types of cups are preferred by the user.

The need for an envelope cup which would retain a predetermined shape when opened has long been recognized and several cups of this type have been devised. The cups of this type heretofore proposed, however, have not come into commercial use for numerous reasons. In the first place, these cups are relatively difficult to make because they involve numerous folds. In the second place they often require more paper than it is economically practical to use. In the third place, and what is probably the most important reason for the failure of these cups to find a commercial market, the cups heretofore proposed do not open readily. If the user is forced to place his finger within the cup in order to open it the cup is not commercially satisfactory. The reason lies not only in possible contamination of the cup, but also in the fact that the failure of the cup to open properly may cause the user to crush it or otherwise damage it. Moreover, the average user does not have the patience and sometimes not the mechanical skill to open a cup of this type if the cup does not open on the first attempt.

One of the objects of the present invention is to provide a new and improved type of paper

cup of the character described which is normally collapsed but will open readily to a pre-determined form and will retain said form when filled with a liquid.

5 Still a further object of this invention is to provide a new and improved cup of the character described which may be cut from a strip of paper with a minimum amount of waste.

Another object of the invention is to provide a new and improved cup of the character described having certain new and improved features which assist in the opening of the cup.

10 Other objects and advantages of the invention will appear by reference to the following description in conjunction with the accompanying drawing, in which:

15 Figure 1 represents a strip of paper which may be taken from a roll and illustrates the manner in which the cup blanks are formed with the sides of the blank forming the edge of the strip;

20 Figure 2 is an enlarged inside view of a cup blank used to form paper cups in accordance with this invention;

25 Figure 3 is a side elevational view of a paper cup formed in accordance with this invention, said cup being in its flat or collapsed state;

30 Figure 4 is a view in perspective illustrating the appearance of the cup of Figure 3 when opened ready for use;

35 Figure 5 is an enlarged cross-section taken through the line 5—5 of Figure 3;

Figure 6 is a cross-section taken through the line 6—6 of Figure 3;

Figure 7 is a cross-section taken through the line 7—7 of Figure 3;

Figure 8 is a cross-section taken looking upward through the line 8—8 of Figure 3;

Figure 9 is a cross-section taken looking upward through the line 9—9 of Figure 3.

40 Referring to Figure 1, it will be seen that the cups may be formed directly from a strip S. The blanks from which the cups are formed may be die-cut from the strip and then formed into a cup or the cup may be formed directly on the end of the strip so that in effect no blank is previously cut. Thus, a cup is first formed on the

45 end of the strip from the area C indicated by the heavy lines in Figure 1. Thereafter the strip is advanced and a second cup is formed from the area D indicated by the dotted lines. In either case the edges of the strip S form two straight side edges 2 and 4 of the cup area C.

50 When the cup is formed the edge 6, having a tab portion 8, is turned over along the line 10 so that the rounded edge of the paper may be used

as a drinking edge and does not tend to cut the lips of the user. The remainder of the mouth of the cup is formed from the arcs 12 and 14 which are of such radii that they coincide with each other when the cup is formed. As shown, according to the particular embodiment herein illustrated, the arc 12 is somewhat longer than the arc 14. Furthermore, the center line M—M of the blank is off center and does not coincide with the center line of the strip S. The shape of the blank is accordingly unsymmetrical.

As shown in Figure 2, the cup is made up with a number of fold lines which are illustrated by the dotted lines. These fold lines divide and form the boundaries for certain areas of the cup. Thus, the side wall area W is bounded at the top by line 16—18, on the sides by lines 16—20, 18—22, and at the bottom fold lines 20—24, 24—26 and 22—26. When the cup is formed the areas W' and W'' overlap each other and are secured together by adhesive G. The two areas W' and W'' when thus joined together form the other side wall of the cup. The area W'' is bounded on one side by fold line 16—20 and fold line 20—28, on another side by fold line 28—30, on the third side by edge 4 and on the fourth side by edge 14. The area W' is bounded on one side by fold line 18—22 and fold line 22—32, on another side by fold line 32—34, on the third side by edges 36 and 2 and on the fourth side by edge 12.

The base of the cup is formed from a plurality of fold portions, some of which also open up to form a portion of the side walls of the cup when the cup is opened and ready for use. These latter portions are the triangular areas Y and Z shown in Figure 4. The base itself, as shown in Figure 4, is the square or substantially square portion X.

Referring again to Figure 2, the triangular area Y of Figure 4 is made up of areas Y' and Y'', shown in Figure 2. The area Y' is bounded by fold lines 20—24, 24—38 and 20—38, and the area Y'' is bounded by fold lines 20—28, 20—38 and 28—38, as shown in Figure 2. The area Z of Figure 4 is made up of the two areas Z' and Z'', shown in Figure 2. The area Z' is bounded by fold lines 22—26, 22—40 and 26—40 and the area Z'' is bounded by fold lines 22—32, 22—40 and 32—40.

The area X which makes up the square base portion of the cup, as shown in Figure 4, is made up of the areas X₁, X₂, X₃ and X₄, shown in Figure 2. The areas X₁ and X₂ are adapted to overlap the areas X₃ and X₄, respectively, when the cup is formed and the areas X₃ and X₄ are adhesively secured to the areas X₁ and X₂ by means of the glue line G₁ shown in Figure 2.

The area X₁ is bounded by fold lines 26—40, 26—42, 40—44 and the edge 42—44. The area X₂ is bounded by fold lines 32—40, 40—44, 32—46 and the edge 44—46.

On the other side of the blank the area X₃ is bounded by fold lines 24—48, 24—38, 38—50 and the edge 48—50. The area X₄ is bounded by fold lines 28—38, 28—52, 38—50 and the edge 50—52.

Referring again to Figure 4, it will be seen that the base X is overlapped by triangular fold portions A and B. As shown in Figure 2, the triangular fold portion A is made up of areas A₁, A₂, A₃ and A₄. The triangular fold portion B is made up of fold portions B₁, B₂ and B₃. The area A₁ is bounded by fold lines 28—30, 28—54 and edge 30—54. The area A₂ is bounded by fold lines 28—52, 28—54 and edge 52—54. The

area A₃ is bounded by fold lines 32—46, 32—56 and edge 46—56. The area A₄ is bounded by fold lines 32—56, 32—34 and edge 34—56.

When the cup is formed the area A₃ is overlapped by the area A₄. The area A₄ in turn is overlapped by the area A₂ and the area A₂ is overlapped by the area A₁, as shown by the cross-section in Figure 5. The entire triangular fold portion A, made up of areas A₁, A₂, A₃ and A₄ is arranged to overlap the area X₂, which in turn overlaps the area X₄.

The triangular fold portion B, shown in Figure 4 and made up of the areas B₁, B₂ and B₃, shown in Figure 2, is adapted to overlap the base area X₁, which in turn overlaps the base area X₃, as shown by the cross-section in Figure 5.

In forming the cup from the blank illustrated in Figure 2, the wings W' and W'' which form one of the side walls are brought upwardly assuming the blank is lying in the flat position, as shown in Figure 2, thereby forming creases along lines 18—22 and 16—20, which creases form side edges of the cup, as shown in Figure 3. These side edge creases extend in a generally outward direction with respect to the interior of the cup. A reverse crease extending inwardly is formed along the line 22—44 on one side and along the line 20—50 on the other side of the cup. For convenience the creases extending in the general direction of 18—22 will be referred to as outside creases, while the creases extending in the general direction of crease 22—44 will be referred to as inside creases. Outside creases are also formed along the lines 22—56 and 20—54. Likewise outside creases are formed along the lines 30—38, 24—38, 24—26, 26—32 and 32—34. Inside creases are also formed along the lines 24—48 and 26—42.

It will be observed that the creases 32—46, 18—44 and 26—42 are substantially parallel and oblique to the center line M—M. The same is true with respect to the creases 28—52, 16—50 and 24—48. The positions of the glue lines G and G₁ are such that when the cup is folded along the creased lines indicated the various fold portions will be glued together and the bottom of the cup will be sealed in such a way as to be substantially liquid tight. This is made possible by the arrangement of the base fold portion and the overlapping arrangement of the triangular fold portions A and B at the base. If desired the triangular fold portions A and B may be glued to the bottom of the base by applying an adhesive in a suitable area of the opposite side of the blank.

The drinking edge or mouth of the cup which is formed along the fold line 16—18 (also crease 10) is held in position by adhesive area G₂.

One of the features of this invention resides in the provision of a cup which will open readily and easily. A feature of the construction which contributes toward this end is to be found in the arrangement of the bottom folds so that the amount of material adjacent the center of the cup when it is in a flat or envelope cup shape is much greater than the amount of material adjacent the sides thereof. This is clearly illustrated by reference to Figure 9, which is a cross-section looking upward taken through line 9—9 of Figure 3. By inspection it will be seen that the thickness of material adjacent the center of the cup is approximately three times the thickness of the material adjacent the side. This difference in the thickness of the material at the center and at the side is also illustrated by comparing Figures 6 and 7 wherein Figure 6

indicates the relative proportion of material at the center of the cup and Figure 7 the relative proportion of material adjacent one side. The greater concentration of material at the center area is also illustrated by Figure 5, which is a cross-section taken through the center of the cup along the line 5—5 of Figure 3.

What is perhaps more important as a feature of the present invention is the position of the adhesive or glue areas in superposed relationship between the folds of the material adjacent the center of the base. It will be observed that there are substantially no glue areas adjacent the side edges. Thus, by placing the adhesive or glue areas in the central folds the resiliency and weight of the glue further tend to increase the ease with which the cup will open. This arrangement is possible because the side walls of the cup are formed from the upper part of the blank and the base of the cup from the lower part of the blank. It would not be possible to accomplish this result, for example, if the base of the cup were placed in the central portion of the blank and if the cup were formed by a saddle fold or a central fold. Furthermore, in accordance with the present invention the side walls of the cup are sealed by means of only a single glue line as contrasted with the use of a double glue line in many types of envelope cups heretofore manufactured. The use of a double glue line has the disadvantage that it adds to the cost of manufacture. Additionally the presence of several glue lines in the sides of the cups increases the possibility of leakage.

It will be understood that the specific embodiment of the invention is given for the purpose of illustration only and that other variations and modifications may be made without departing from the invention.

Having thus described the invention, what I claim as new and desire to secure by Letters Patent of the United States is:

1. A drinking cup of the envelope type adapted to assume a pre-determined shape when opened by lateral pressure against the side edges thereof, said cup being formed from a flexible sheet material with the upper part of said flexible sheet material forming the side walls of the cup and the lower part forming the base of the cup, said base part being folded in such a manner as to permit opening of the cup to a pre-determined shape and with a substantially greater number of folds of said material adjacent the center of said base portion than at the side edges from which the cup is opened, and creased oblique-opening planes integral with said base and said side walls and forming oblique planes thereto when said cup is fully opened.

2. A drinking cup of the envelope type adapted to retain a pre-determined shape when opened, said cup being formed from a blank of flexible sheet material, the upper part of said blank forming side walls of said cup bounded by longitudinally extending side wall creases, the lower part of said blank forming the base of the cup and being divided into a plurality of planes extending substantially parallel with respect to the side walls of the cup when said cup is in its normally collapsed condition, fold lines in said base planes permitting said cup to open to a pre-determined shape when pressure is exerted against said side wall creases, and creased oblique-opening planes integral with said base planes and said side walls and forming oblique planes thereto

when said cup is opened by exerting pressure against said side wall creases.

3. A drinking cup of the envelope type adapted to retain a pre-determined shape when opened, said cup being formed from a blank of flexible sheet material, the upper part of said blank forming side walls of said cup bounded by longitudinally extending side wall creases, the lower part of said blank forming the base of the cup and being divided into a plurality of planes extending substantially parallel with respect to the side walls of the cup when said cup is in its normally collapsed condition, fold lines in said base planes permitting said cup to open to a pre-determined shape when pressure is exerted against said side wall creases, and creased oblique-opening planes integral with said base planes and said side walls and forming oblique planes thereto when said cup is opened by exerting pressure against said side wall creases, the concentration of material toward the center of the base being substantially greater than at the sides from which the cup is opened.

4. A drinking cup of the envelope type adapted to retain a pre-determined shape when opened by lateral pressure against side edges thereof, said cup being formed from a blank of flexible sheet material, the upper part of said blank forming side walls of said cup bounded on opposite sides by longitudinally extending side wall creases, the lower part of said blank forming the base of the cup and being divided into a plurality of planes extending substantially parallel with respect to the side walls of the cup when said cup is in its normally collapsed condition, fold lines in said base portion permitting it to open to a flat bottom when pressure is exerted against said side wall creases, and creased oblique-opening planes integral with said flat-opening base portion and said side walls and forming oblique planes therewith when said cup is opened, said oblique planes being bounded on two sides by creases which also bound the side walls of the cup and on a third side by creases which define in part said flat-opening base portion.

5. A drinking cup of the envelope type adapted to retain a pre-determined shape when opened by lateral pressure against side edges thereof, said cup being formed from a blank of flexible sheet material, the upper part of said blank forming side walls of said cup each of which is bounded by common longitudinally extending creases, the lower part of said blank forming the base of the cup and being divided into a plurality of adjacent planes extending substantially parallel with respect to the side walls of the cup when said cup is in its normally collapsed condition, fold lines in said base part permitting said cup to open to a pre-determined shape when pressure is exerted against said side wall creases, creased oblique-opening planes integral with said base portion and with said side walls and forming oblique planes therewith when said cup is opened, and creased overlap portions integral with said side walls and with said base.

6. A drinking cup of the envelope type adapted to retain a pre-determined shape when opened by lateral pressure against side edges thereof, said cup being formed from a blank of flexible sheet material, the upper part of said blank forming side walls of said cup each of which is bounded by common longitudinally extending creases, the lower part of said blank forming the base of the cup and being divided into a plurality of adjacent planes extending substantially parallel with re-

spect to the side walls of the cup when said cup is in its normally collapsed condition, fold lines in said base part permitting said cup to open to a pre-determined shape when pressure is exerted against said side wall creases, creased oblique-opening planes integral with said base portion and with said side walls and forming oblique planes therewith when said cup is opened, and creased overlap portions integral with said side walls and with said base, the arrangement of said folds and creases being such as to form a several times greater bulk of material toward the center of the base than at the sides from which the cup is opened.

7. A drinking cup of the envelope type adapted to retain a pre-determined shape when opened by lateral pressure against side edges thereof, said cup being formed from a blank of flexible sheet material, the upper part of said blank forming the side walls of said cup each bounded on opposite sides by a common longitudinally extending side wall crease, the lower part of said blank forming the base of the cup and being divided into a plurality of adjacent planes extending substantially parallel with respect to the side walls of the cup when said cup is in its normally collapsed condition, fold lines in said base part permitting said cup to open to a pre-determined shape when pressure is exerted against said side wall creases, creased oblique-opening triangular planes integral with said base portion and with said side walls and forming oblique planes therewith when said cup is opened, and triangular overlap sealing portions integral with said side walls and said base and secured to said base in overlapping relationship.

8. A drinking cup of the character described formed from a blank of flexible sheet material, the upper part of said blank forming side walls of said cup each bounded on opposite sides by a common longitudinally extending side wall crease, the lower part of said blank forming the base of the cup and being divided into a plurality of planes extending substantially parallel with respect to the side walls of the cup when said cup is in its normally collapsed condition, fold lines in said base portion permitting it to open to a substantially flat bottom when pressure is exerted against said side wall creases, and creased oblique-opening planes integral with said flat-opening base portion and with said side walls and form-

ing oblique planes therewith when said cup is opened, said flat-opening base portion being defined in part by creases bounding said oblique planes, in part by the edge of the blank and in part by creases bounding fold portions adapted to overlap said base portion, and said oblique planes being bounded on two sides by creases which also bound the side walls of the cup and on a third side by creases which define in part said flat-opening base portion.

9. A drinking cup of the character described formed from a blank of flexible sheet material, the upper part of said blank forming side walls of said cup each bounded by common longitudinally extending creases, the lower part of said blank forming the base portion of said cup, said base portion being made up of a plurality of areas on opposite sides of the center line of the cup defined at least in part by creases, two of said areas on each side of the center line of the cup being secured together to form the base of the cup, two other areas on each side of the center line of the cup adjacent said base areas being arranged to open into oblique planes when the cup is opened, a plurality of said areas bounded in part by a base of the side wall of the cup and in part by the edges of said base areas forming a sealing portion and another plurality of areas bounded in part by the base of the other side wall and in part by the opposite edges of the base area forming a second sealing portion, said sealing portions being adhesively secured to said cup.

10. A drinking cup of the envelope type adapted to retain a pre-determined shape when opened, said cup being formed from a blank of flexible sheet material, part of said blank forming side walls of said cup bounded by longitudinally extending side wall creases, part of said blank forming the base of the cup and being divided into a plurality of planes extending substantially parallel with respect to the side walls of the cup when said cup is in its normally collapsed condition, fold lines in said base planes permitting said cup to open to a pre-determined shape when pressure is exerted against said side wall creases, and creased oblique-opening planes integral with said base planes and said side walls and forming oblique planes thereto when said cup is opened by exerting pressure against said side wall creases.
